UNITED STATES PATENT OFFICE.

GEORGE D. LIVINGSTON, OF MINNEAPOLIS, MINNESOTA, ASSIGNOR TO ROBERT B. WHITACRE, OF ST. PAUL, MINNESOTA.

LIQUID-WEIGHER.

1,223,593.

Specification of Letters Patent. Patented Apr. 24, 1917.

Application filed October 19, 1914. Serial No. 867,434.

To all whom it may concern:

Be it known that I, GEORGE D. LIVINGSTON, a citizen of the United States, residing at Minneapolis, in the county of Hennepin and State of Minnesota, have invented certain new and useful Improvements in Liquid-Weighers, of which the following is a specification.

My invention relates to improvements in automatic liquid weighers designed particularly for weighing and registering the amount of feed water that is supplied to the boiler of an engine. Its objects are to provide apparatus which can be interposed 10 in the water supply system and which will automatically weigh the amount of water passing through it to the boiler or boiler feed pump, and which will be simple and strong in construction and efficient in operation. In carrying out the invention I have devised apparatus whereby the inflowing water is automatically distributed into charges of predetermined weight and the charges are delivered to a storage tank from 20 which it can be fed to the boiler or other place of use as desired.

More particularly the invention consists in the construction, combination, and arrangement of parts hereinafter described 30 and claimed.

In the accompanying drawings showing an embodiment of the invention,

Figure 1 is a front elevation of the improved apparatus partly broken away;

Fig. 2 is a front elevation of the apparatus on an enlarged scale with some parts broken away;

Fig. 3 is a rear elevation thereof partly broken away;

Fig. 4 is a side view thereof also partly broken away; and

Figs. 5 and 6 are details partly in section, of the two float lever clutches, as seen from the yoke between them so that the opposing 45 inner sides of the float arms are exposed.

In the drawings 2 represents a feed water supply pipe having a downturned discharge elbow 3. Below the elbow is a tank having two similarly shaped compartments 50 4 and 5, respectively, of equal size arranged symmetrically side by side and separated by means of an upright partition wall 6 which extends nearly to the top of the tank in line with the vertical axis of the elbow 3. Below this tank is a storage tank A having

an outlet pipe. In the bottom of each compartment is a valve 7, the knuckle of which is operated by means of a valve rod 8 extending up through the compartment. The valves and valve rods are arranged symmetrically on each side of the partition wall 6. A swinging cylindrical spout 9 is pivotally suspended from the elbow 3 by means of horizontal pivots 10 at front and rear, so that it will oscillate upon a transverse horizontal axis and can be swung across the top of the partition wall to direct the flow of water first into one compartment and then into the other.

Secured to the top of the partition wall 70 at the rear of the spout is a bracket 11 having upstanding end lugs in which is mounted a longitudinal pin 12. Rotatably supported upon this pin adjacent to the spout is a combined valve and spout lever having 75 a cross arm 13, the ends of which are pivotally connected with the tops of the valve rods 8, and a central upstanding arm 14 carrying a transverse pin 15, one end of which projects into the space between two 80 parallel guide lugs 16 upon the rear of the spout whereby to move the spout, so that when the valve and spout lever is oscillated, it will not only operate the valve rods but also swing the spout across the top of the 85 partition 6. In this operation the valves 7 will be alternately opened and closed, one of them being opened through the same movement of the lever which closes the other and vice versa, while the spout will be 90 swung from the compartment in which the valve is being opened to that in which the valve is being closed.

The spout and valve lever is operated 95 through the medium of a top-weighted lever 17 formed at the top with a transversely extending opening and journaled at the bottom upon the pin 12. This element 17 is here shown as a skeleton sectoral shaped lever yoke having its apex at the bottom 100 where it is journaled upon the pin 12. At the top this lever yoke has a central upwardly extending arm 18 upon which is a weight 19, so that when the yoke stands with the rod in vertical position it will be 105 in unstable equilibrium and ready to drop over to one side or the other. The valve and spout lever is operated by this yoke through the medium of its pin 15, one end of which, as has been stated, stands between the guide 110

lugs 16 on the spout, while the other end extends through the opening in the lever yoke, where it will be engaged and moved by one or other of the side arms of the yoke when the yoke is thrown over in either direction.

5 The yoke itself is operated by means of a pair of float lever arms 20, each of which carries at its outer end a float 21 of usual construction. The float arms are journaled 10 upon the pin 12 at front and rear, respectively, of the lever yoke 17 and in close proximity thereto. The hub of each float arm has a clutch lug 22 on its inner side in 15 position to engage a co-acting clutch lug 23 upon the adjacent side of the hub of the lever yoke, so that when the float lever arm turns to carry its lug 22 against the lug 23 of the yoke, the yoke will be turned upon its axis until the arm 18 passes beyond the 20 vertical position, when the yoke will suddenly drop over on the other side under its own weight. As it drops it will strike and carry with it the pin 15 upon the spout and valve lever, thereby turning the lever as 25 above described. In Figs. 5 and 6 are shown the relative positions of the clutch lugs upon the two float arms and the yoke when the yoke is in upright position, as shown in Fig. 3, the float arms being shown as seen from 30 the yoke between them, so that their inner sides are shown.

When the apparatus is at the beginning of its operation, both tank compartments will be empty. If then the yoke lever is 35 thrown over toward one of the tank compartments, for instance the compartment numbered 4, it will throw the valve and spout lever over in the same direction, thereby closing the valve 7 in the compartment 4 and swinging the mouth of the spout so that 40 it will discharge the flowing water into that compartment. As the water rises in the compartment it will lift the float therein and turn the float lever upwardly. As the 45 float lever rises its lug 22, bearing against the lug 23 on the yoke, will in turn lift the yoke and turn it on the pin 12 until the float has nearly reached the top of the tank and the yoke stands in the upright position 50 shown in the drawings. Then any further rising of the float will push the weighted yoke beyond its position of unstable equilibrium and cause it to drop quickly over toward the other tank compartment 5. In its 55 drop it will strike and carry with it the pin 15, thereby with a quick movement at once opening the valve in the full compartment 4 and closing the valve in the empty compartment 5, as well as swinging the mouth of the 60 spout across the partition wall from compartment 4 to the compartment 5. When the yoke falls its weight will rest at first upon the pin 15, thereby holding down the spout and valve lever and keeping the valve 65 closed in compartment 5, and when the yoke

is gradually lifted from the pin by the rising float, the valve will be held down by the ever increasing pressure of the rising water.

While the water is thus rising in the compartment 5 it will be discharging from the 70 compartment 4 through the valve 7 into the storage tank below, so that the float in this compartment will drop as the water level recedes. As the float rises in compartment 5 it will gradually lift the yoke up to and beyond its upright position of unstable equilibrium, when the yoke will drop over again toward the now empty compartment with a sudden throw, thereby closing the valve in that compartment and opening the valve in 80 the filled compartment 5, and at the same time swinging the spout from the filled compartment to the empty compartment in the manner already described. This operation will continue automatically and continuously as long as the flow of water is allowed 85 to continue through the pipe 2. When the water in the storage tank rises to a certain level the supply through the pipe 2 can be cut off automatically or otherwise by suitable 90 valve and float connections (not shown).

Thus the charges of water will always be equal in volume and weight, so that to determine the weight of the water passing into the boiler it is only necessary to calculate 95 the weight of one of the charges and multiply it by the total number of charges. If desired the number of charges can be registered upon a dial 24, as shown in Fig. 1, by means of suitable mechanism not shown, 100 connected with the yoke by means of a connecting rod 25, or in any other suitable way.

When the tank compartments for any reason are made shallow, the weight of the water upon the valves will be smaller than 105 in the case of a deeper tank, so that it may be desirable to apply additional pressure to the valve. For this purpose I have provided as a supplementary pressure device a tube 26 partly filled with mercury or some other 110 heavy instrumentality that will flow or run easily through the tube when the same is tilted. The tube is arranged across the apparatus and is pivotally supported upon the valve lever 13 by means of the arms 27, so 115 that it will swing with the valve lever. The tube has at each end a bulb 28. Thus when the valve lever arm is inclined downward the tube will be inclined with it and the mercury will flow into the bulb at the lower 120 end thereof thus exerting pressure on the valve rod 8 and the closed valve.

I claim as my invention:

1. In an automatic liquid weigher, the combination with a source of liquid supply, 125 of a pair of tanks having outlet valves, an oscillatory spout adapted to direct the flow of liquid into one or other of said tanks according to the direction in which it is swung, an oscillatory valve lever operatively con- 130

nected at its opposite ends with the valves in said respective tanks, a top weighted element having a transversely extending opening at the top and a pivotal support at its 5 lower end, a lateral pin carried by said valve lever and extending into the opening in the top weighted element, an operative connection between said lever and said spout, and floats actuated by the rise of the liquid in 10 the tank which is being filled and operative to turn the top weighted element until the center of gravity thereof is shifted to the other side of its pivotal support, whereby the top weighted element will drop over and 15 strike the pin upon the valve lever, thereby throwing said lever and swinging the spout.

2. In an automatic liquid weigher, the combination with a source of liquid supply, of a pair of tanks having outlet valves, an 20 oscillatory spout adapted to direct the flow of liquid into one or the other of said tanks, according to the direction in which it is swung, an oscillatory valve lever operative to open and close the valves in said 25 respective tanks, a top weighted lever having a pivotal support at its lower end, a pair of floats loosely mounted upon said pivotal support on opposite sides of said top weighted lever, one of said floats working within one 30 tank and the other float within the other tank, coöoperating means upon the floats and weighted lever, whereby said lever will be lifted and turned by one or other of the floats as the float rises in its tank, an operative 35 connection between said valve lever and the spout, and means carried by the valve lever in position to be engaged by the weighted lever when the same is turned so far that its center of gravity is shifted to the other 40 side of its pivotal support, whereby the valve lever is turned and the mouth of the spout is shifted from one tank to the other.

3. In an automatic liquid weigher, the combination with a source of liquid supply, 45 of a pair of tanks having outlet valves, an oscillatory spout adapted to direct the flow of liquid into one or other of said tanks according to the direction in which it is swung,

an oscillatory valve lever operative to open and close the valves in said respective tanks 50 and having an upstanding arm, a top weighted lever having a pivotal support at its lower end, and formed with a transversely extending opening, a lateral pin carried by said arm and engaging the spout at 55 one end and extending into the opening in the top weighted lever at the other end, a pair of floats mounted on said pivotal support and working within said tanks respectively, and coöoperating clutch lugs upon 60 the floats and top weighted lever whereby each float as it rises in the tank will engage and turn said lever, thereby causing said lever to drop over and strike said pin when it has been turned so far as to shift its center 65 of gravity to the other side of its pivotal support, whereby to turn the valve lever and swing the spout.

4. In an automatic liquid weigher, the combination with a source of liquid supply, 70 of a pair of tanks having outlet valves, an oscillatory spout adapted to direct the flow of liquid into one or the other of said tanks according to the direction in which it is swung, an oscillatory valve lever operatively 75 connected at its opposite ends with the valves in said respective tanks and having an upstanding arm, a top-weighted skeleton yoke having a pivotal support at its lower end, a lateral pin carried by said arm and engaging the spout at one end and extending through the yoke at the other end, and means actuated by the rise of the liquid in the tank which is being filled for turning the yoke until its center of gravity is shifted to 80 the other side of its pivotal support, whereby the yoke will drop over and engage said pin, thereby turning the valve lever and swinging the spout.

In testimony whereof I affix my signature 90 in presence of two witnesses.

GEORGE D. LIVINGSTON.
